UNITED STATES PATENT OFFICE

107,531

DESIGN FOR A PARKING METER HOUSING

Raymond Loewy, New York, N. Y., assignor to
The Karpark Corporation, New York, N. Y.

Application April 12, 1937, Serial No. 68,708

Term of patent 14 years

To all whom it may concern:

Be it known that I, Raymond Loewy, a citizen of the Republic of France, residing at New York, in the county of New York and State of New York, have invented a new, original, and ornamental Design for a Parking Meter Housing, of which the following is a specification, reference being had to the accompanying drawing, forming part thereof.

The figure is a perspective view of a parking

meter housing, showing my new design. It will be understood that the sides of the housing which are not shown are substantially the same as those seen in the drawing. Likewise, it will be understood that the numerical designations, appearing in the drawing, are purely illustrative.

I claim:

The ornamental design for a parking meter housing, as shown and described.

RAYMOND LOEWY.
